UNITED STATES PATENT OFFICE.

RICHARD WHITAKER, OF NEW BRUNSWICK, NEW JERSEY, ASSIGNOR TO
THE NEVERSLIP MANUFACTURING COMPANY, OF SAME PLACE.

DESIGN FOR A HORSESHOE-CALK.

SPECIFICATION forming part of Design No. 27,542, dated August 17, 1897.

Application filed April 7, 1897. Serial No. 631,173. Term of patent 14 years.

To all whom it may concern:

Be it known that I, RICHARD WHITAKER, a citizen of the United States, residing at New Brunswick, in the county of Middlesex and State of New Jersey, have invented and produced a new and original Design for Horseshoe-Calks, of which the following is a specification, reference being had to the accompanying drawings, forming part thereof.

10 Figure 1 is a perspective view of a horseshoe-calk, showing my design. Fig. 2 is a side elevation of the same, these two views being deemed necessary to fully illustrate my design.

15 The leading feature of my design consists in a part-way cylindrical and part-way milled or serrated collar under a conical point having a semispherical end and projecting over and beyond the sides of its screw-threaded

shank. In other words, it consists in the unitary design forming the subject of the accompanying drawings.

In the drawings, A is the collar, which is cylindrical in its general contour, but its lower half (or slightly more than half) is milled or provided with vertical serrations a. Under said collar is the shank B, on which is cut a screw-thread b, slightly tapering toward its outer end, and upon said collar there is the point C, which is conical, with its end blunt and semispherical.

What I claim is—

The design for a horseshoe-calk substantially as herein shown and described.

RICHARD WHITAKER.
